United States Patent Office

Des. 200,704
Patented Mar. 30, 1965

200,704

CHAIR

Edward M. Rogers, Jr., Birmingham, Ala., assignor to
Birmingham Ornamental Iron Company, Inc., Birmingham,
Ala., a corporation of Alabama

Filed Nov. 7, 1963, Ser. No. 77,324

Term of patent 14 years

(Cl. D15—1)

Fig. 2

Fig. 3

FIGURE 1 is a front elevational view of a chair back showing in detail the dominant feature of my design;

FIGURE 2 is a top plan view; and

FIGURE 3 is a rear elevational view thereof.

FIGURE 4 is a front perspective view of a chair showing my design.

The dominant features of my design reside in those portions shown in full lines on the drawing.

I claim:

The ornamental design for a chair, as shown and described.
